(57) **CLAIM**

The ornamental design for a frame as shown and described.

DESCRIPTION

FIG. 1 is a front, top, and left perspective view of a frame showing my new design;

FIG. 2 is a rear, bottom, and left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion indicated with the number 9 in FIG. 1; and,

FIG. 10 is an enlarged view of the portion indicated with the number 10 in FIG. 2.

The broken lines shown in the drawings represent portions of the frame that form no part of the claimed design.

1 Claim, 10 Drawing Sheets
